UNITED STATES PATENT OFFICE.

PATRICK J. GRIFFIN, OF BOSTON, MASSACHUSETTS.

DESIGN FOR A CAP FOR AIR-VALVES.

57,639.

Specification for Design. Patented Apr. 26, 1921.

Application filed February 4, 1921. Serial No. 442,550. Term of patent 7 years.

To all whom it may concern:

Be it known that I, PATRICK J. GRIFFIN, a citizen of the United States, residing at Dorchester, Boston, in the county of Suffolk, State of Massachusetts, have invented a new, original, and ornamental Design for a Cap for Air-Valves, of which the following is a specification, reference being had to the accompanying drawing, forming a part thereof.

Figure 1 is a side elevation of a cap for air valve showing my new design, Fig. 2 is a top view thereof, and Fig. 3 is a view

in side elevation representing the said cap applied to a portion of a wheel rim and serving to identify more specifically the article to which the design is applied.

I claim:

The ornamental design for a cap for air valve as shown.

In testimony whereof I affix my signature in presence of two witnesses.

PATRICK J. GRIFFIN.
